WELL STRAINER

Leslie A. Layne, Houston, Tex.

Application May 5, 1936, Serial No. 77,903

1 Claim. (Cl. 166—6)

This invention relates to well strainers and more particularly to frames for supporting the straining element.

It is an object of the invention to provide a frame which will present a minimum of obstruction to inward flow.

Another object of the invention is to provide a frame of economical construction.

Other objects and attendant advantages will appear in the following description of one practical embodiment of the invention illustrated in the accompanying drawing, in which

Fig. 1 is a vertical cross section of a well screen embodying the present invention.

Fig. 2 is a fragmentary transverse sectional view of the well screen shown in Fig. 1 and illustrating the insert therein.

Fig. 3 is a fragmentary inside elevational view of the frame, and showing the wire type of strainer, and

Fig. 4 is a fragmentary inside elevational view of a modified form of the frame construction.

The well screen illustrated in the drawing comprises a frame 10 which is made up of an upper nipple member 11 and a lower nipple member 12 connected together by spaced bars 13. The bars 13 are cut away at 14 on the inside of the ends thereof and are arranged to fit over the reduced ends 14 on each of the couplings 11

and 12. The bars 13 are connected together at spaced intervals by internal rings 16, the bars and the rings being formed with complementary recesses 17 and 18 designed to interfit to form mortised joints.

If desired, the frame and strainer wire may be made of corrosion proof material such as stainless steel and in this manner a very substantial construction is provided.

In the construction of the frame 10 the bars and rings are first assembled and welded or otherwise attached after which the couplings 11 and 12 are added and fixed to the ends of the bars. The modified form of frame illustrated in

Fig. 4 differs from that illustrated in Fig. 1 in that the rings 16 are located on the outside of the bars.

It will be noted that the bars and rings in both constructions are spaced a large distance apart in order to offer a minimum of interference to inward flow of the fluid. It will also be noted that the joints between the rings 16 and the bars 17 are made flush so as not to interfere with the windings of the wire 19.

It should be particularly noted that the complementary interfitting recesses of the bars and the ring serve to fix the parts in their relative position and the close fitting shoulders of the recesses reinforce the adjoining parts to form a firm joint.

When the frame 10 is assembled then the openings 19 formed by the bars and rings are ready to receive the inserts such as 20. Such an insert is seen in Fig. 2 and comprises a body 21 formed with suitable gauge openings 22 so that a strainer of the proper size is thus formed. It should be noted that the walls 23 and 24 of the bars are substantially parallel so that the inserts may be moved into position and they may thereafter be welded in position if desired. When all of the openings are filled the strainer will be complete, light in weight and compact while being sufficiently rigid to withstand the stresses applied.

In lieu of the inserts 20, however, a wire strainer member 25 may be wrapped around the frame in a manner well known in applying strainer wire to perforated pipe.

Broadly the invention contemplates an economical and durable frame for well strainers.

What is claimed as new is:

A strainer for wells comprising a frame, said frame including longitudinally spaced bars, spaced annular rings engaged to said bars, and strainer inserts disposed in the openings formed by said bars and rings.
